United States Patent Office

Des. 232,562
Patented Aug. 27, 1974

232,562

TELEPHONE STAND

Francis Stephen Doyle, Oaklandon, Ind, Donald Michael Genaro, Haworth, N.J., and Terrance Joseph Paas, and Terry Brice Prince, Indianapolis, Ind., assignors to Bell Telephone Laboratories Incorporated, Murray Hill, N.J.

Filed May 29, 1973, Ser. No. 364,703

Term of patent 14 years

Int. Cl. D14—03

U.S. Cl. D26—14 A

FIG. 1

FIG. 2

FIG. 1 is a perspective view showing the top, right side, and a portion of the front of our new design for a telephone stand;

FIG. 2 is a rear view of the telephone stand;

FIG. 3 is a side view of the telephone stand, the opposite side being essentially a mirror image of the side shown; and

FIG. 4 is a front perspective view of the telephone stand.

We claim:

The ornamental design for a telephone stand, substantially as shown and described.
